UNITED STATES PATENT OFFICE

94,072

DESIGN FOR A FLOWER HOLDER

Samuel Cantor, Brooklyn, N. Y.

Application June 5, 1934, Serial No. 52,064

Term of patent 7 years

To all whom it may concern:

Be it known that I, Samuel Cantor, a citizen of the United States, residing at Brooklyn, in the county of Kings and State of New York, have invented a new, original, and ornamental Design for a Flower Holder, of which the following is a specification, reference being had to accompanying drawing, forming part thereof.

The flower holder is made of relatively thin glass with the outer surface smooth and with the interior surface formed in scallops, as shown.

I claim:

The ornamental design for a flower holder as shown and described.

In testimony whereof I affix my signature.

SAMUEL CANTOR.
